FASTENER-ATTACHING MACHINE

Harry Levine, Brooklyn, N. Y., assignor to American Eyelet Co., Inc., New York, N. Y., a corporation of New York

Application February 19, 1938, Serial No. 191,392

15 Claims.

(Cl. 1—2)

This invention relates to fastener attaching machines, and more particularly to such machines intended to attach to an envelope a metal fastener designed to keep the flap of the envelope closed.

The primary object of my invention is to generally improve fastener attaching machines of the class described, and more particularly, a machine for handling and attaching an H-shaped fastener with fastener arms projecting from the cross-bar of the H and tangs formed at the ends of the H.

Machines for handling and attaching fasteners of this type have been designed, in which the fasteners are preliminarily formed with the tangs bent at right angles to the fastener, these fasteners then having to be suitably hoppered in order to position the same in uniform sequential arrangement for feed to the attaching machine. It is far more economical and convenient to use flat blanks, a large number of which may be compactly stacked in a magazine, and in accordance with one feature and object of my invention, the H-shaped blanks are stacked in flat condition, and the machine is provided with a preliminary bending station at which the tangs of the fastener blank are bent before the blank is fed to the attaching station.

More particular objects of my invention center about the feed of the blank to and from the bending station, and in accordance with my invention, two separate feed mechanisms are provided, one serving to push the flat blank from the magazine to the bending station, and the other including a pair of pull fingers notched to receive the arms of the blank and resiliently urged downwardly, said fingers functioning to draw the fastener away from the bending station after the bending operation. This separate feed has the advantage of holding the fastener by the arms during the bending operation, despite the downward movement of the fastener at that time; of holding the fastener downwardly on the feed rails leading to the bending station during the first feed operation from the magazine; of acting as a stripper to strip the bent fastener from the bending punch during upward movement of the punch after the bending operation; and of preventing one fastener from jamming on top of another because the bent fastener is fed away from the bending station in a positive manner before a succeeding blank is fed to the bending station.

A further object of my invention is to transfer the bent fastener from the bending station to

the attaching station in a convenient and simplified manner. For this purpose, I provide a stationary chute fixedly mounted on the frame of the machine and leading to a point adjacent the attaching punch. The fastener is delivered from the chute and rests temporarily on retractable support arms located beneath the punch. As the punch descends and takes hold of the fastener, the support arms are retracted, thereby clearing the path for movement of the fastener and punch toward the anvil beneath the punch.

Further objects of my invention center about the attaching punch and are, first, to hold the fastener against movement during retraction of the support arms; and second, to closely surround and rigidly support the tangs of the fastener in order to prevent outward spreading or collapsing of the tangs during the attaching operation. This is of particular importance when the fastener must penetrate paper which is particularly heavy, or tough in texture and fibre.

Still further objects of the present invention concern the anvil for turning the tangs inwardly and clenching the same in place. For convenience, I shall refer to the inturning of the tangs as "curling", in order to distinguish from the sharp, right-angle bending of the tangs from the flat blank at the bending station. It will be understood, however, that the tangs, while curved somewhat as they are turned inwardly, are not really curled around in the sense of a full convolution or more. Such object of my invention is to hammer the tangs flat against the inside surface of the envelope. This prevents papers or articles from catching on the tangs, and eliminates the possibility of scratching one's hand when placing the same in the envelope. An anvil which is satisfactory for flattening the tangs is unsatisfactory for preliminarily curling the tangs, as they pass through the paper; and an anvil which satisfactorily curls the tangs is unsatisfactory for hammering the same flat at the end of the attaching stroke of the punch. This is particularly true when using a simple reciprocating punch movement with no horizontal moving jaws or mechanism in the anvil. Such mechanism not only complicates the machine, but is altogether impractical when, as in the present case, the anvil is mounted on a relatively slender pointed horn over which the mouth of the envelope is slipped preparatory to the fastening operation.

In accordance with my invention, the anvil is made of two relatively movable parts, one being a curling part having a slot cut therethrough to

receive the tangs, the ends of said slot being sloped to form camming surfaces for curling the tangs. The other part of the anvil includes a male element slidably receivable in the slot. The curling part is normally urged upwardly by resilient means, but toward the end of the punch stroke, this part is forced downwardly so far that the male element reaches a point flush with the top of the curling part and thus functions to hammer the tangs into perfectly flat condition. In fact, the tangs may be partially embedded in the paper, and can hardly be felt or noticed when inserting one's hand in the envelope. With the special H fastener here employed, a pair of slots 15 may be used, one for each side of the H.

To the accomplishment of the foregoing, and such other objects as will hereinafter appear, my invention consists in the fastener attaching machine elements and their relation one to the other, 20 as hereinafter are more particularly described in the specification and sought to be defined in the claims. The specification is accompanied by drawings, in which:

Fig. 1 is a side elevation of a machine embodying features of my invention;

Fig. 2 illustrates the shape of the fastener blank being handled by the machine as here illustrated;

Fig. 3 shows the manner in which the fastener 30 is applied to an envelope;

Fig. 4 is a side elevation of the plunger and delivery chute, showing the fastener support arms in retracted position;

Fig. 5 is a partially sectioned elevation explanatory of the feed mechanism at the bending station;

Fig. 6 is a transverse section through the bending die taken in the plane of the line 6—6 of Fig. 5;

Fig. 7 is a plan view of the horn and anvil;

Fig. 8 is a section taken in elevation through the plunger and anvil mechanism, the section through the latter being approximately in the plane of the line 8—8 of Fig. 7;

Fig. 9 is a transverse section through the anvil taken in the plane of the line 9—9 of Fig. 7;

Fig. 10 is a horizontal section through the plunger sleeve taken in the plane of the line 10—10 of Fig. 9;

Fig. 11 is a view like Fig. 9, but showing the relation of the parts at the end of the attaching operation;

Fig. 12 is a partially sectioned elevation similar to Fig. 8, but showing the relation of the parts 55 at the end of the fastener attaching operation; and

Fig. 13 is a perspective view explanatory of the feed mechanism at the bending station.

Referring to the drawings, the fastener is made 60 of a blank like that shown in Fig. 2. The blank is approximately H-shaped, and has fastener arms 12 projecting outwardly from the cross-bar 14 of the H. The ends of the H are pointed as shown at 16, and when these points are bent as 65 shown at 18, they form tangs for attaching the fastener to the envelope. The method of attachment and use of the fastener will be evident from Fig. 3, showing a fragment of the complete envelope. The body of the envelope is made up of a back wall 20, the edges of which are folded into overlapping relation, as is indicated at 22, in order to form the front wall 24 of the envelope body. The flap 26 projects upwardly from the envelope back 20 and may be 70 turned downwardly at fold line 28 in order to

close the envelope. The flap is provided with a perforation 30 preferably reinforced by a patch 32. When the flap is folded over, this perforation registers with the center of the fastener 34. The fastener is secured by means of the four pointed tangs 16 which pass through the overlapping part 22 of the front wall of the envelope body, and which are clenched and preferably hammered flat therebehind. The fastener arms 12 are turned upwardly when the envelope is being closed, and the opening 30 in the flap passes over the arms 12, which are then restored to outward spread condition, thus locking the flap against opening.

Referring now to Fig. 1 of the drawings, a 15 stack of fastener blanks 36 is disposed in a suitable preferably upright magazine 38. The arms of the blanks extend toward the sides of the machine, that is, perpendicularly to the drawing. The bottom-most blank is fed by an appropriate 20 pusher finger at the inner end of a feed bar 40 from magazine 38 to a bending station B. Here the tangs are bent at right angles to the blank, whereupon the bent blank is fed by pull fingers 42 into a preferably stationary delivery chute C 25 which transfers the fastener downwardly to the attaching station A. The machine is provided with a suitable horn H, and the envelope is slipped with its mouth or open end over the horn H to a point determined by appropriate 30 locating stops not shown in the drawings. The plunger P then descends and attaches the fastener to the envelope. The opening for the flap is preferably also punched during the same operation, thus helping ensure proper registration of 35 the opening and the fastener, but this punching mechanism forms no part of the present invention, and has not been included in the drawings.

Considering the mechanism in greater detail, and referring more particularly to Figs. 5 and 13 40 of the drawings, the stack of blanks 36 in magazine 38 rests at its lower end on a surface 44 formed at the rear end of a pair of feed rails 46. The pusher finger 48 is slidably in a recess 50, and the height of the pusher finger 48 is so gauged 45 as to bear against the bottom-most blank and to slide it forwardly from the magazine over the rails 46. During this feed movement the blank is held downwardly on the rails by the end portions 52 of the pair of pull fingers 42. The pull fingers 50 are secured to a connecting pin 54 which is oscillatable in links 56. The fingers 42 are urged downwardly by a pull spring 58 the lower end of which is secured to an arm 60 projecting from pin 54.

The first feed movement of the blank carries it to the bending station B. It is there retained by recesses 62 formed on the lower edges of pull fingers 42. The pull fingers are provided with sloping camming surfaces 64 leading to recesses 60 62, thus facilitating the feed of the blank to the recesses. It will be understood that these recesses receive the arms 12 of the blank. The inner side walls 66 of the feed rails 46 act as the female part of the bending die. These walls are 65 slotted at 68 to permit downward movement of the blank during the bending operation. The blank at this time rests on a spring pad 70 best shown in Figs. 5 and 6. Pad 70 is carried at the upper end of a guide rod 72. The pad is normally moved upwardly by compression springs 74, and the upward movement is limited by a stop pin 76. In this uppermost position, the pad 70 comes flush with the feed rails 46, and thus permits the fastener to be fed from the bending 70 75

station B to the delivery chute C by the pull fingers 42. The spring pad resists downward movement of the male bending punch 78, and thereby holds the blank against lateral movement during the bending operation.

Fig. 6 shows the relation of the parts after beginning of the bending operation, with the tangs 16 partially bent toward their final perpendicular upwardly pointing position. The spring pad 70 acts as an ejector to push the bent fastener upwardly out of the die after the bending operation. The pull fingers 42 act as strippers to strip the fastener from punch 78 should it happen to adhere to the punch instead of to the die. It will be understood that the fingers 42 move downwardly with the blank during the bending operation and at no time lose their fit around the fastener arms 12. This is illustrated by the downwardly inclined position of the pull fingers 42 shown in Fig. 13 of the drawings. The spring pad 70 has been omitted in Fig. 13 in order to clarify the construction of the feed rails 46.

At the end of the bending operation, the feed fingers 42 are pulled to the right as viewed in Fig. 5, thus moving them from the solid to the broken-line position 42'. This brings the bent fastener to the guide channel 80 in chute C. Channel 80 is formed between spaced members 82 and 84, and it will be understood that member 84 is small enough in dimension to be straddled by the bent tangs 16 of the fastener. The pull fingers 42 have not been drawn completely in broken lines in Fig. 5, in order not to confuse the drawing, but enough of the fingers has been drawn to indicate the position of the recess 62 at 62', and it will be seen that this is at or slightly beyond the beginning of the guide track 80 of the chute. The fastener falls down the chute gravitationally.

Reverting to Fig. 1, the pusher feed finger is mounted at the forward end of a feed bar 40. This is reciprocated by lever 90 pivoted at 92 and carrying at its opposite end a cam follower roller 94. This cooperates with a cam 96 carried on a main time shaft 98. Shaft 98 is preferably provided with a single revolution clutch in conventional manner, the operation of the machine then being controlled by an appropriate lever or treadle. The arrangement is such that for each depression of the treadle, the shaft 98 turns through a single revolution, and this puts the machine through one complete cycle of operation. The operator then applies another envelope to the horn H and again releases the machine for one complete operation.

The pull fingers 42 are also operated from lever 90. For this purpose the feed fingers are pivotally connected at their forward ends to arms 56 secured to and depending from a shaft 100 to which is secured an arm 102, said arm 102 and the arms 56 forming in combination an angle lever. The shaft 100 is carried on a stationary support 104 which is fixedly mounted on the machine frame. Arm 102 is connected by a long link 106 to the lower arm 108 of lever 90. It will be evident from inspection, that the parts move in opposite direction, that is, when lever 90 swings in clockwise direction, the pusher finger moves to the right, transferring a blank from the magazine 38 to the bending station B, and at the same time the pull fingers 42 are moved to the left in order to engage the arms of the blank. When lever 90 swings counterclockwise, the pull fingers 42 move to the right, and transfer the bent fastener to the chute C, while bar 40 moves to the left, back to-

ward the magazine. Hence jamming of one fastener on top of another is prevented.

The bending punch 78 is formed at the forward end of an arm 160 secured to shaft 162 which also carries arm 164 connected to a link 166, which in turn is connected at 168 to a cam follower lever 170. Lever 170 is oscillatably mounted on the machine frame at 172 and carries a cam follower roller 174 which bears against a cam 176 mounted on cam shaft 98. It will be clear that for each revolution of cam 176, the bending punch 78 is moved through one stroke at bending station B.

The attaching station is next described with reference to Figs. 8 through 12 of the drawings. The fastener descends through track 80 of the stationary chute C and is discharged onto a support 110 formed at the lower end of a generally upright arm 112. The fastener is properly located along support 110 by a pair of locating fingers 114, these being secured to the stationary chute at 116, 20 and only the rear one of which is shown in the drawings. (The nearer one is visible in Fig. 4.) Fingers 114 are spaced apart (in a direction perpendicular to the drawing) further than the width of punch sleeve 118, so that the punch can 25 pass freely between the fingers 114. These fingers catch the long sidewardly projecting fastener arms 12 and thereby position the fastener along support 110. The location of the fastener sidewardly of the support 110 is determined by the 30 down-turned tangs 16. The useful working part of support 110 is located symmetrically in front of chute C and beneath punch 120, although the arm 112 is disposed alongside chute C.

The attaching punch assembly comprises a 35 main part 120 the bottom face 122 of which is flat and has an area corresponding to the dimension of the H-shaped part of the fastener. Punch 120 is closely surrounded by sleeve 118, and the parts are relatively slidable. For this purpose the 40 punch is slotted at 124, while sleeve 118 is provided with a pin 126 extending across the sleeve and slidable in slot 124. A relatively light compression spring 128 is carried in the shank 130 of the punch, and its lower end bears downwardly on 45 pin 126 and consequently tends to keep the sleeve 118 in the lowered position shown in Fig. 8. The side edges of sleeve 118 are cut away at 132 to receive the fastener arms 12. As the punch assembly descends, the sleeve 118 fits around the 50 fastener and the arms 12 are received in notches 132. The fastener is then supported against movement upon retraction of the support 110 from the position shown in Fig. 8 to the position shown in Fig. 12. The fastener manifestly can- 55 not move to the right with the support 110 because the fastener arms 12 are already engaged by notches 132 of the sleeve 118. The fastener does not drop downward, because it is rather snugly received in sleeve 118, that is, there is at 60 least a slight frictional resistance between the tangs 16 and the walls of the sleeve, and this is adequate to prevent the light sheet metal fastener from falling downwardly ahead of the punch.

The fastener is then carried downwardly with 65 the punch until the tangs 16 reach the paper of the envelope on horn H. The relation of the parts at this time is shown in Fig. 9, in which it will be seen that the tangs 16 have just reached the envelope wall 134. The sleeve 118 comes to 70 rest, and punch 120 descends against the top of the fastener. It carries the fastener downwardly until the tangs penetrate the paper and are bent inwardly or curled, as is indicated by the broken line position 16'. An important advantage of the 75

sleeve 118 is that it bears against the outside of the tangs 16 during the attaching operation and prevents the tangs from bending or buckling outwardly even when encountering substantial resistance due to the paper 134 being unusually heavy or tough-fibred. This close fit of the sleeve 118 about the fastener will be clearly understood from inspection of Fig. 10. At the same time, it may be explained that it is the side walls 136 of the sleeve that are important both in providing the notches 132 for arms 12, and in providing support for the tangs 16. The other side walls 138 are unimportant and may be omitted or cut away. They are preferably retained in order to form strengthening walls which interconnect the operating walls 136, but in any case are cut away somewhat at the bottom, to receive the support 110. They are preferably cut away to a height equal to the height of recesses 132.

20 Reverting again to Fig. 1, the shank 130 of the punch is carried in the lower end of a vertically reciprocable plunger P. This is slideable in bearings formed in arms 140, 142. The plunger is connected at 144 with a lever 146 pivoted within 25 the machine frame at 148 and having a rearward and downward extension 150 at the lower end of which is mounted a cam follower roller 152 co-operating with a cam 154 mounted on cam shaft 98. It will be evident that rotation of cam 154 causes one stroke of plunger P for each cycle of 30 operation.

The retractable support 110 is carried on a long arm 112 which is pivotally mounted on frame part 142 at pivot 156. The inner edge of arm 112 is shaped to form a cam surface 158, and this cooperates with a roller 160 mounted at the forward end of lever 146. It will be seen from inspection and comparison of Figs. 1 and 4 that as the plunger descends, the support 110 is retracted, and 40 the timing of retraction is made such that the sleeve 118 comes around the fastener before the support is retracted, all as was previously described.

The anvil carried by the horn H is of improved 45 construction, and may be described with reference to Figs. 7 through 12. The anvil comprises two relatively movable parts, one being a curling part 180 and the other being a flattening part 182. To fit the present fastener, the curling part 180 is 50 provided with a pair of slots 184 which are cut entirely through the member 180. The ends of slots 184 are beveled or sloped at 186 in order to form surfaces which turn the points of tangs 16 inwardly. This slope may be made a steep one, and 55 may be best selected for nicely turning the tangs inwardly, because there is unlimited depth to the slots 184. The operation is clearly shown by the broken-line position of the tangs 16' in Fig. 9. In this specification I term this operation 60 "curling" in order to distinguish the same from the bending operation at the station B.

The entire curling plate 180 is slidably received 65 in horn H or in the stationary flattening part 182 of the anvil. The curling part 180 is normally elevated by stiff compression springs 188. The upward movement of part 180 may be limited by a pair of screws 190, the heads of which are set in flush with horn H and beneath which a ledge 192 is received. The resistance of springs 70 188 is such that the tangs 16 are curled before the curling part 180 is depressed by the punch. The hammering of the tangs to flat condition therefore takes place only after the tangs have been preliminarily curled.

75 The stationary part of the anvil is provided

with a pair of flattening members 182 which are slidably received within the slots 184, as is clearly shown in the drawings. When the punch 120 reaches the bottom of its pressure stroke, it forces the curling part 180 downwardly into the stationary part of the anvil until the flat top surfaces of the flattening parts 182 become substantially flush with the top of the movable part 180. At this time the tangs 16 are hammered into a tightly closed and perfectly flat condition, as 10 will be understood from inspection of Figs. 11 and 12 of the drawings.

Reverting to Fig. 1, it may be remarked that the entire horn H is itself slightly movable in a vertical direction, it being pivoted at 194. This is conventional practice in order to avoid the necessity of rigidly supporting the horn. Instead, it is permitted to move downwardly a short distance until it rests on the bed plate 196, at which time the lower side of the envelope is compressed between the horn and the bed plate, while the upper side of the envelope is compressed on the top side of the horn. The stroke of the plunger P is made adequate to drive the fastener into tightly flattened condition after all of the relative movements of the parts heretofore described, have 20 taken place.

It is believed that the construction and operation as well as the many advantages of my improved fastener attaching machine, will be apparent from the foregoing detailed description thereof. A supply of flat fastener blanks is stacked in magazine 38. An envelope is slipped over the horn H. At this time a previously made fastener is already resting on retractable support 35 110. A suitable treadle or other starting lever is operated, thus putting the machine through a single cycle of operation. During this cycle of operation, the fastener on retractable support 110 is secured to the envelope, and at the same time 40 a new fastener blank is bent at the bending station B and delivered to the chute so that it will be available for attachment to the next envelope. The double-action feed at the bedding station has the advantage of holding the blank on the guide 45 rails during the feeding operation; of holding the blank by the arms during the bending operation; of ensuring stripping of the bent fastener from the bending punch as well as ejection of the fastener from the die; and of preventing one 50 fastener from jamming up on top of another, for the bent fastener is delivered to the chute during retraction of the pusher finger and long before feed of the next blank from the magazine.

The delivery of the bent fastener to the attaching station is through a stationary chute fixedly mounted on the machine, and this avoids any difficulty with smooth sliding action of the fastener at the upper end of the chute. The attaching punch not only functions to drive the fastener, 60 but also holds the fastener in position during retraction of the support 110. Moreover, the sleeve closely surrounding the tangs supports the same against outward bending or buckling during the attaching operation.

The anvil combines in an advantageous manner two conflicting requirements, first, the provision of sloping camming surfaces for curling the tangs, together with a deep receptive slot therebeneath to receive the tangs during the curling operation; and second, the provision of an exceedingly shallow anvil, or even better, a flush, flat anvil top for hammering the bent tangs into perfectly flat condition. These conflicting requirements are met by the provision of relative- 75

ly movable parts, one for curling, and one for flattening, the tangs. The resulting improved operation is obtained without complicating the machine or requiring additional parts driven from the cam shaft, and instead, all of the desired movements are obtained as a result of a single downward stroke of the plunger.

It will be apparent that while I have shown and described my invention in a preferred form, many changes and modifications may be made in the structure disclosed, without departing from the spirit of the invention defined in the following claims.

I claim:

1. Anvil mechanism for a fastener attaching machine, said machine handling H-shaped fasteners having fastener arms projecting from the bar of the H and tangs bent at the ends of the H, said anvil mechanism comprising relatively movable curling and flattening parts, said curling part having a pair of slots cut therethrough to receive the tangs, the ends of said slots being sloped to form camming surfaces for curling the tangs, the upper large end of the slots being long enough to receive the tangs before curling the same, the flattening part including a pair of male elements slidably receivable in the lower small ends of the slots of the curling part, said male elements being shorter than the spacing of the tangs prior to curling, but long enough to engage the tangs as they are curled by the sloping ends of the slots, and means yieldably urging said curling part away from the flattening part.

2. Anvil mechanism for a fastener attaching machine, said machine handling H-shaped fasteners having fastener arms projecting from the bar of the H and tangs bent downwardly from the ends of the H, said anvil mechanism comprising relatively movable curling and flattening parts, said curling part having a pair of slots cut therethrough to receive the tangs, the ends of said slots being sloped to form camming surfaces for curling the tangs, the upper large end of the slots being long enough to receive the tangs before curling the same, the flattening part including a pair of male elements slidably receivable in the lower small ends of the slots of the curling part, said male elements being shorter than the spacing of the tangs prior to curling, but long enough to engage the tangs as they are curled by the sloping ends of the slots, springs normally urging said curling part upwardly relative to the flattening part, means to limit the upward movement of the curling part, said upward movement being adequate to provide ample clearance in the slots for curling of the tangs, the downward movement of said curling part being adequate to bring the flattening part substantially flush with the curling part in order that the tangs may be hammered flat, all in response to a single downward movement of an attaching punch against the anvil.

3. Fastener feeding and bending mechanism for a fastener attaching machine, said machine handling H-shaped fasteners having fastener arms projecting from the cross-bar of the H and having tangs at the ends of the H, said machine comprising a magazine for a stack of flat fastener blanks, means for pushing the lowermost blank from the magazine to a bending station, means for moving said fastener from the bending station to a delivery chute, a bending punch movable downwardly against said blank to force the same into a die and to thereby bend the tangs upwardly at the ends of the H, recesses at the sides of said die for receiving the arms of the fastener during the

bending operation, a spring pad in said die for ejecting the fastener from the die, and means to operate said feed means and said bending punch in proper time sequence.

4. Fastener feeding and bending mechanism for a fastener attaching machine, said machine handling fasteners having fastener arms projecting therefrom, a push finger for pushing the lowermost blank from the magazine to a bending station, pull fingers for moving said fastener from the bending station to a delivery chute, and resilient means normally urging said pull fingers downwardly against the arms of the fastener, said pull fingers having extensions leading toward said magazine for holding the fastener blank downwardly during the first feed movement.

5. Fastener feeding and bending mechanism for a fastener attaching machine, said machine handling H-shaped fasteners having fastener arms projecting from the cross-bar of the H and having tangs at the ends of the H, said machine comprising a magazine for a stack of flat fastener blanks, a push finger for pushing the lowermost blank from the magazine to a bending station, pull fingers for moving said fastener from the bending station to a delivery chute, said pull fingers being recessed at the bottom to receive the fastener arms, resilient means normally urging said pull fingers downwardly against the arms of the fastener, said pull fingers having extensions leading toward said magazine for holding the fastener blank downwardly during the first feed movement and until the fastener arms reach said recesses, and means to operate said push finger and said pull fingers in proper time sequence.

6. Fastener feeding and bending mechanism for a fastener attaching machine, said machine handling H-shaped fasteners having fastener arms projecting from the cross-bar of the H and having tangs at the ends of the H, said machine comprising a magazine for a stack of flat fastener blanks, a push finger for pushing the lowermost blank from the magazine to a bending station, pull fingers for moving said fastener from the bending station to a delivery chute, resilient means normally urging said pull fingers downwardly against the arms of the fastener, said pull fingers having extensions leading toward said magazine for holding the fastener blank downwardly during the first feed movement, a bending punch movable downwardly against said blank to force the same into a die and to thereby bend the tangs upwardly at the ends of the H, recesses at the side of said die for receiving the arms of the fastener during the bending operation, said pull fingers moving downwardly with said fastener during the bending operation, a spring pad in said die for ejecting the fastener from the die, said pull fingers functioning as strippers for stripping the fastener from the punch, and means to operate said push finger, said bending punch and said pull fingers in proper time sequence.

7. A fastener bending and attaching machine for handling fasteners having fastener arms and tangs, said machine comprising a magazine for a stack of blanks in flat condition, a bending station including feed means, a die, and a punch for bending the tangs upwardly, a stationary fixedly mounted chute extending outwardly, downwardly and inwardly for delivering said fastener to an attaching station with the tangs of the fastener pointed downwardly, and attaching means including a horn for receiving an envelope to which the fastener is to be attached, an anvil on said horn, and a punch movable against said anvil.

8. A fastener bending and attaching machine for handling fasteners having fastener arms and tangs, said machine comprising a magazine for a stack of blanks in flat condition, a bending station including feed means, a die and a punch for bending the tangs, a stationary chute fixedly mounted on said machine for delivering the bent fastener downwardly and around onto retractable support arms with the tangs pointing downwardly, stationary stop fingers for engaging the arms of the fastener to locate the same beneath an attaching punch, an anvil beneath said punch, and means to retract said retractable support as the punch descends on the fastener.
9. A fastener bending and attaching machine for handling H-shaped fasteners having fastener arms projecting from the cross-bar of the H and tangs at the ends of the H, said machine comprising a magazine for a stack of blanks in flat condition, a bending station including feed means, a die and a punch for bending the tangs, a stationary chute fixedly mounted on said machine for delivering the bent fastener downwardly and around onto retractable support arms with the tangs pointing downwardly, stationary stop fingers for engaging the arms of the fastener to locate the same beneath an attaching punch, an anvil beneath said punch, means to retract said retractable support arms, and means on said punch for holding the fastener in position when the support arms are retracted.
10. A fastener bending and attaching machine for handling H-shaped fasteners having fastener arms projecting from the cross-bar of the H and tangs at the ends of the H, said machine comprising a magazine for a stack of blanks in flat condition, a bending station including feed means, a die and a punch for bending the tangs, a stationary chute fixedly mounted on said machine for delivering the bent fastener downwardly and around onto retractable support arms with the tangs pointing downwardly, a horn for receiving an envelope to which the fastener is to be attached, an anvil on said horn beneath said punch, means to retract said retractable support arms, and means on said punch for holding the fastener in position when the support arms are retracted.
11. A fastener bending and attaching machine for handling H-shaped fasteners having fastener arms projecting from the cross-bar of the H and tangs at the ends of the H, said machine comprising a magazine for a stack of blanks in flat condition, a bending station including feed means, a die and a punch for bending the tangs upwardly, a stationary chute fixedly mounted on said machine for delivering the bent fastener downwardly and around onto retractable support arms with the tangs pointing downwardly, stationary stop fingers for engaging the arms of the fastener to locate the same beneath an attaching punch, a horn for receiving an envelope to which the fastener is to be attached, an anvil on said horn beneath said punch, means to retract said retractable support arms, and means on said punch for holding the fastener in position when the support arms are retracted.
12. Fastener feeding and bending mechanism for a fastener attaching machine, said machine handling H-shaped fasteners having fastener arms projecting from the cross-bar of the H and having tangs at the ends of the H, said machine comprising a magazine for a stack of flat fastener blanks, a push finger for pushing the lowermost blank from the magazine to a bending station, pull fingers for moving said fastener from the bending station to a delivery chute, resilient means normally urging said pull fingers downwardly against the arms of the fastener, a bending punch movable downwardly against said blank to force the same into a die and to thereby bend the tangs upwardly at the ends of the H, recesses at the sides of said die for receiving the arms of the fastener during the bending operation, said pull fingers moving downwardly with said fastener during the bending operation, a spring pad in said die for ejecting the fastener from the die, said pull fingers functioning as strippers for stripping the fastener from the punch, and means to operate said push finger, said bending punch, and said pull fingers in proper time sequence.
13. A fastener bending and attaching machine for handling H-shaped fasteners having fastener arms projecting from the cross-bar of the H and tangs at the ends of the H, said machine comprising a magazine for a stack of blanks in flat condition, a bending station including feed means, a die and a punch for bending the tangs, a stationary chute fixedly mounted on said machine for delivering the bent fastener downwardly and around onto retractable support arms with the tangs pointing downwardly, stationary stop fingers for engaging the arms of the fastener to locate the same beneath an attaching punch assembly, an anvil beneath said punch assembly, means to retract said retractable support arms, said punch assembly including a punch with a flat bottom surface, the area of said bottom surface corresponding to the area of the H-shaped part of the fastener, side walls outside said punch and slidably relatively thereto, notches at the bottom of the side walls for receiving the arms of the fastener and holding the fastener in position when the support arms are retracted, said side walls closely fitting against the outside of the tangs of the fastener and functioning to support the same against outward bending or buckling during the attaching operation, and resilient means normally urging the side walls downwardly relative to the punch.
14. A fastener bending and attaching machine for handling fasteners having fastener arms and tangs, said machine comprising a magazine for a stack of blanks in flat condition, a bending station including a die and a punch for bending the tangs upwardly, a push finger for pushing the lowermost blank from the magazine to the bending station, a stationary chute extending outwardly, downwardly and inwardly for delivering a fastener to an attaching station with the tangs of the fastener pointed downwardly, pull fingers for moving said fastener from the bending station to the delivery chute, resilient means normally urging said pull fingers downwardly against the arms of the fastener, said pull fingers having extensions leading toward said magazine for holding the fastener blank downwardly, and attaching means including a horn for receiving an envelope to which the fastener is to be attached, an anvil on said horn, and a punch movable against said anvil.
15. A fastener bending and attaching machine for handling fasteners having fastener arms and tangs, said machine comprising a magazine for a stack of blanks in flat condition, a bending station including feed means, a die and a punch for bending the tangs, a stationary chute fixedly mounted on said machine for delivering the bent fastener downwardly and around onto retractable support arms with the tangs pointing down-

wardly, stationary stop fingers for engaging the arms of the fastener to locate the same beneath an attaching punch, anvil mechanism beneath said punch, means to retract said retractable support as the punch descends on the fastener, said anvil mechanism comprising relatively movable curling and flattening parts, said curling part having a slot cut therethrough to receive the tangs, the ends of said slot being sloped to form camming surfaces for curling the tangs, the upper large end of the slot being long enough to receive the tangs before curling the same, the flattening part including a male element slidably receivable in the lower small end of the slot of

the curling part, said male element being shorter than the spacing of the tangs prior to curling but long enough to engage the tangs as they are curled by the sloping ends of the slot, springs normally urging said curling part upwardly relative to the flattening part, said upward movement being adequate to provide ample clearance in the slot for curling of the tangs, the downward movement of said curling part being adequate to bring the flattening part substantially flush with the curling part in order that the tangs may be hammered flat. 5 10
